US0D1029090S

(12) **United States Design Patent** (10) Patent No.: US D1,029,090 S
Crystal et al. (45) Date of Patent: ** May 28, 2024

- (54) **ELECTRONIC CUTTING MACHINE**

(71) Applicant: **Cricut, Inc.**, South Jordan, UT (US)

(72) Inventors: **Jeremy Crystal**, Springville, UT (US);
Clark L Roper, North Highland, UT (US); **James T. Davis, II**, Springville, UT (US); **Jim Colby**, Highland, UT (US); **Jeffrey V Gubler**, Orem, UT (US); **Alan Romig**, Stansbury Park, UT (US); **Steven Bandis**, West Jordan, UT (US)

(73) Assignee: **Cricut, Inc.**, South Jordan, UT (US)

(**) Term: **15 Years**

(21) Appl. No.: **29/915,485**

(22) Filed: **Oct. 31, 2023**

Related U.S. Application Data

- (63) Continuation of application No. 18/466,571, filed on Sep. 13, 2023, which is a continuation of application No. 17/484,050, filed on Sep. 24, 2021, now Pat. No. 11,782,413, which is a continuation of application No. 14/768,405, filed as application No. 11,782,413.

Primary Examiner — Lauren D McVey

CLAIM

The ornamental design for an electronic cutting machine, as shown and described.

DESCRIPTION

The FIGURE is a front, right, top isometric view of the electronic cutting machine in an open configuration.

(Continued)

The broken lines immediately adjacent the shaded areas represent the bounds of the claimed design, while all other broken lines are directed to environment; the broken lines form no part of the claimed design.
